COLLAPSIBLE BOX

Glen E. Hartman, Oklahoma City, Okla., assignor to Oklahoma Paper Company, Oklahoma City, Okla., a corporation of Oklahoma

Application February 15, 1937, Serial No. 125,731

6 Claims. (Cl. 229—41)

This invention relates to boxes generally, and particularly to those made of fibrous material such as cardboard, strawboard, or the like, and which may be folded or collapsed for shipping or storage, and unfolded and set up as needed.

Among the objects of my invention is to provide a collapsible box of this kind, which will be neat and attractive in appearance, sturdy so as to stand up well in actual service, extremely economical as compared with non-collapsible boxes used for the same purposes, and which will be otherwise satisfactory and efficient for use wherever deemed applicable.

One of the important objects of this invention is to provide a box of the kind described, which will be especially useful for the delivery of men's or ladies' hats, although it is not intended that the field of usefulness of the box shall be confined to such articles, and wherein said box shall preferably be of polygonal shape in transverse cross-section to conform to the discriminating and expensive trade using such articles.

Another object of my invention is to provide such a box, made of two main elements, one of which shall compose the enclosing side walls of the box, and the other of which shall be permanently associated therewith and form the bottom of the box, and reinforce each other against accidental collapsing while the box is in set up position.

An added object of the invention is to provide a box of the kind described, in which the bottom will be raised above the supporting rim of the box, thereby minimizing any tendency of the set up box to seat unevenly.

A further object of my invention is to provide a box of the kind described, wherein a tie member is associated with the two main elements, so that when the latter are in collapsed position the tie member will be sufficiently loose to permit of such collapsed relationship, and the pulling taut of said tie member will actuate both of said collapsed elements from their collapsed position towards their set up relationship, and act as a reinforcement beneath said bottom to support the latter against downward thrust and load and prevent accidental re-collapsing of the box.

A still further object of this invention is to provide reentrant inturned flanges on the bottom edges of the side walls of the box, and foldable peripheral flanges on said bottom element, the latter flanges being interposed between said first flanges and said side walls to limit the bottom element against further downward movement past said side wall flanges and maintain said bot-

tom element spaced above the supporting edges of the box, and also assisting in preventing accidental collapsing of the box.

Another object of the invention is to provide a collapsible lid for a polygonal box, so that such lids may be shipped and stored similarly to the boxes themselves, and may be opened and set up as needed, simply by unfolding the lids from their collapsed position.

Many other objects and advantages of the construction herein shown and described will be obvious to those skilled in the art to which this invention appertains, from the disclosures herein given.

To this end my invention consists in the novel construction, arrangement and combination of parts herein shown and described, and the uses mentioned, as will be more clearly pointed out in the claims.

In the drawing, wherein like reference characters indicate like or corresponding parts throughout the views,

Fig. 1 is a perspective view, of the container, with parts broken away.

Fig. 2 is a perspective view of the lid.

Fig. 3 is a perspective view of the container in partly collapsed position.

Fig. 4 is a sectional view of Fig. 3.

Fig. 5 is a plan view of the bottom.

Referring more particularly to the drawing, wherein I have illustrated one of the preferred embodiments of my invention, there is shown a receptacle or box made of fibrous and relatively cheap material, such as from cardboard, strawboard, corrugated paper, or the like, and of a shape well-liked for use in the retail distribution of men's and ladies' hats.

The box as shown is substantially polygonal in form, the instant embodiment showing a hexagonal box for example, and comprising two main elements, the enclosing or wall element A and the bottom element B, associated with a tie member T to assist in drawing said elements into set-up position and supportingly reinforcing the box in use.

By making the bottom element B separate and independent of the side walls, the variety of combinations in material and pattern, colors, etc., is greatly widened, and hence, one is not limited to a bottom element of the same appearance as the side wall structure. This is quite important in many instances, especially where the retailer has a desire for an individually patterned box, say for example, a light-colored side wall enclosure and a dark bottom element.

45

55

55

The enclosure element A is preferably formed of a sheet of the desired material, having a series of substantially parallel score lines 1—1 extending vertically to define the side walls or panels 2 of the box, there being six of these panels in the box shown, and the adjoining ends of said panels are permanently connected so as to make an integral structure. The lower ends of said side walls are bent or folded reentrantly inwardly 10 to form peripheral flanges 3 to lie substantially parallel with the side walls, so that the box will be supported on a double thickness of material at its periphery, making for strong and sturdy construction where needed.

15 The bottom element B comprises a main body portion 4 of the same sized hexagonal form as the interior of the set-up side wall element A, each of said bounding edges of the bottom element being provided with a score line to provide 20 peripheral flanges 5 of a depth preferably substantially equal to the depth of the flanges 3, the ends of adjacent flanges 5 being separated from one another so as to permit of said bottom element and its flanges being extended into a 25 plane.

This bottom element is secured at a pair of parallel peripheral edges to the side wall element, as by staples or the like, 6 to make a permanent securing thereof, the secured pair 30 of flanges 5 being interposed between the adjacent panels and their flanges 3, so that substantially the full depth of the flanges 5 are within the flanges 3 to enable the uppermost or free edges of said flanges 5 to support the bottom 35 element therealong.

The bottom element B is provided with another score line or crease 7 extending substantially centrally or median between the pair of secured flanges 5, diametrically of said bottom 40 element, so that when said element is secured at its pair of opposed flanges 5 to the corresponding lower ends of the wall element A, and the element B is folded double along said diametral line of fold 7 inwardly of the element A, the latter will be also folded double along the pair of 45 score lines defining the panels, adjacent the ends of said fold line 7. Thus, when so folded to collapsed position, the wall element will be folded double for the full height of its panels, and the line of fold 7 will be transversely at right angles 50 to said lines of vertical fold of the element A.

The unsecured flanges of the bottom element, will, of course, be interposed in the spaces between the corresponding lower ends of the side 55 walls and their flanges to interlock said elements against accidental collapse, but in order to facilitate the setting up of the box, with easy insertion and positioning of the flanges of the bottom element to proper place, I have provided a tie 60 member T, as for example, the cord or ribbon indicated.

This tie member is threaded at either end, in sequence, through a flange 5, flange 4, and lower edge of a panel of the side wall element A, 65 projecting exteriorly beyond the latter and of sufficient length to be tied across the top of the box. It will be noted that said tie member extends transversely across the box, below the bottom element B, at an angle to the diametral 70 fold line 7, so that when taut, said tie member will supportingly reinforce said bottom element whenever the latter is pressed thereagainst, as for example when the box is loaded heavily.

When it is desired to set up one of the boxes 75 from collapsed position, the opposite ends of

the tie member are pulled apart, thus drawing the bottom element substantially flat and unfolded across the bottom of the element A, swinging the free flanges 5 into position into the spaces between the corresponding panels of the 5 box and their flanges 3, until said tie is taut, and if necessary the flanges of the bottom element may be pressed into final position from within the box. Obviously, the tie member extending transversely across said median line of 10 fold of the bottom element will, in addition to providing a reinforcing support for the load, prevent accidental separation and collapsing of the box.

A polygonal lid L may be similarly collapsibly 15 constructed for such a polygonal box, said lid being of a sheet of desired material, similar to or contrasting with that of the box or any of the two portions thereof, the central or body portion of said lid being of a polygonal area of 20 a size to fit over and cover the top of the box when set up, as indicated at 8.

Depending from the bounding side edges of said central or body portion 8 are the flanges 9 integrally connected to one another properly 25 scored vertically to form the defining sides of the polygon. The opposite ends of alternate flanges project beyond and are superimposed onto the ends of the adjacent flanges and secured 30 thereof, as by staples 10 or the like. Each 35 of said alternate flanges so projected, is provided with a score or crease extending diagonally from the adjacent corner of the lid, inwardly and downwardly to the lower or free edge of said flanges, as at 11, so that the flanges may be 40 folded along said diagonal creases and said vertical folds substantially flat against the body portion, and thereby permit of stacking the lids similarly to the packaging of the boxes themselves.

In order to relieve the stress that is placed on 40 the material of the box at the fold lines, when folding the same double, and avoid the breaking of the same at or adjacent the fold lines, I have found it highly desirable to cut away the material of the flanges adjacent one another in either 45 direction away from the vertical lines where the box is folded double, as best illustrated in Figs. 4 and 5. These cut-outs may be in the shape of the substantially triangular openings there 50 shown, or in any other shape wherein the ends of the reentrant flanges will come together at the lines of double fold 1 at substantially but a point of material, or perhaps slightly spaced 55 from one another without contact at all, the rest of the opposed areas of these opposed ends being increasingly separated to their lines of juncture with the bottom edge of the side walls.

Having thus set forth my invention, it is obvious that various immaterial modifications may be made in the same without departing from the 60 spirit of my invention; hence I do not wish to be understood as limiting myself to the exact form, arrangement, construction and combination of parts herein shown and described, except as limited by the state of the art to which this 65 invention appertains, and the claims hereunto appended.

What I claim as new and desire to secure by Letters Patent is:

1. A collapsible box comprising a wall element 70 constituting a series of integrally connected side walls adapted to be folded double to collapsed position, the lower ends of said walls having in-turned reentrant flanges; a separate bottom element having a diametral fold at right angles to 75

- the fold line of said wall element and provided with peripheral flanges, said bottom element being permanently secured at a pair of opposed flanges to said side walls; and a tie member freely extended entirely below said bottom element transversely thereacross and threaded through the flanges of both elements and thence projecting exteriorly through the lower ends of said wall element, so that when the elements are set up from collapsed position said flanges of the bottom will be interposed between said side wall element and its flanges and said tie member will supportingly reinforce the bottom element when the latter is pressed thereagainst.
5. A collapsible polygonal box, comprising a wall element having a series of adjoined similar side wall panels adapted to be folded flat their full height, and provided with inturned reentrant flanges at the lower ends; an independent bottom element, having peripheral flanges adapted to be interposed between said side panels and their flanges and secured permanently in position at a pair of diametrically opposed flanges only, said element having a central line of fold 5 parallel to said pair of flanges; and a tie member extending transversely of said line of fold of said bottom element, substantially entirely below the latter and threaded through a pair of flanges of the bottom element and the adjacent side panels and their flanges, whereby pulling said tie member in opposite directions will unfold said elements simultaneously and draw the flanges of the bottom element into place between the side panels and their flanges.
10. 2. A collapsible polygonal box, comprising a wall element having a series of adjoined similar side wall panels adapted to be folded flat their full height, and provided with inturned reentrant flanges at the lower ends; an independent bottom element, having peripheral flanges adapted to be interposed between said side panels and their flanges and secured permanently in position at a pair of diametrically opposed flanges only, said element having a central line of fold 10 parallel to said pair of flanges; and a tie member extending transversely of said line of fold of said bottom element, substantially entirely below the latter and threaded through a pair of flanges of the bottom element and the adjacent side panels and their flanges, whereby pulling said tie member in opposite directions will unfold said elements simultaneously and draw the flanges of the bottom element into place between the side panels and their flanges.
15. 3. A two-member collapsible receptacle comprising an element adapted to be folded double to collapsed position and constituting a series of side walls provided with a reentrant substantially U-shaped supporting edge at the lower end; a bottom element having a diametral fold to be folded double to collapsed position within said first element and permanently secured at a pair of opposed peripheral edges to the lower end of said first element and having opposed peripheral flanges, said bottom element adapted to be supported in opened position on the lower end of said first element; and a tie member threaded through the first element from the exterior diametrically through the lower ends of said first element and through said peripheral flanges and thence immediately extending entirely below said bottom element to reinforce the latter when the latter is pressed against the taut tie member.
20. 4. A collapsible box comprising an element having a series of side walls and adapted to be folded double to a collapsed position and provided with peripheral flanges folded inwardly substantially parallel to said side walls so as to support the box on said lowermost fold; a separate bottom element having a median fold and 5 pairs of opposed peripheral flanges and permanently secured at one of said pairs of opposed flanges only to said side wall; and a tie member extended below said bottom element transversely of the fold line of said bottom element, and 10 through another pair of flanges of said bottom element, and thence threaded outwardly through said side walls above said folded supporting edge of the latter, whereby the tautening of said tie member will pull the bottom element against the 15 side wall to close the box thereat.
25. 5. A collapsible box comprising a member having a series of side walls provided with a peripheral flange folded reentrantly to support the box on the lowermost folded edge, and said 20 member being foldable double to a collapsed position; a separate bottom member having a median fold so as to be folded double within said first member and having pairs of opposed peripheral flanges and permanently secured at one 25 pair of opposed flanges only to said side walls; and a tie element extended along and below said bottom member transversely of the bottom fold line and thence threaded outwardly of the box through said side walls and another pair of said 30 flanges of said bottom member entirely above the lowermost supporting edge of said side wall flanges so as to pull the member from collapsed position to substantially straight position as the tie element is made taut.
35. 6. A collapsible box comprising a wall element constituting a series of side walls adapted to be folded to collapsed position, the lower portion of said walls having inturned reentrant flanges; a separate bottom element having a diametral 40 fold at right angles to the fold line of said wall element and provided with peripheral flanges, said bottom element being permanently attached at its flange to said side walls; and a tie member freely extended entirely below said bottom 45 element transversely thereacross and threaded through the flanges of the same and thence projecting exteriorly through the lower ends of said wall element, so that when the elements are set up from collapsed position, said flanges of the 50 bottom element will be interposed between said side wall element and its flanges, and said tie member will supportingly reinforce the bottom element when the latter is pressed thereagainst.

GLEN E. HARTMAN. 55
